Inventor.
E. S. Bennett

ERASTUS S. BENNETT, OF NEW YORK, N. Y., ASSIGNOR TO HIMSELF AND JUSTUS SMITH, OF SAME PLACE.

Letters Patent No. 86,127, dated January 26, 1869; antedated January 11, 1869.

IMPROVEMENT IN LIFE-PRESERVERS.

The Schedule referred to in these Letters Patent and making part of the same.

To all whom it may concern:

Be it known that I, ERASTUS S. BENNETT, of the city, county, and State of New York, have invented a new and improved Method of Constructing Life-Preservers; and I do hereby declare that the following is a full and exact description thereof, reference being had to the accompanying drawings, and to the letters of reference marked thereon.

The advantages to be derived from the use of my preserver are many and obvious. It can, when not in use, be folded in compact form, for convenient carriage in the reticule or pocket; can be furnished at a moderate price, can be easily and quickly applied, cannot slip from its proper position or be lost, gives its support mainly to the head of the wearer, does not interfere with the free use of the arms in swimming, or assisting others, or in casting off heavy weights, water-soaked clothing, skirts, boots, &c., and, in emergencies, will supply sufficient air to maintain life several moments under water.

As an aid to those learning to swim, it is invaluable, since the buoyancy, besides being secured at the proper point, can be instantly adjusted to the requirements of the learner, its position being such as permits the most perfect freedom in the use of the limbs.

To enable others skilled in the art to make and use my invention, I will proceed to describe its construction and operation.

In the annexed plate, Figure No. 1 represents a perspective view of the life-preserved as made by me.

A A, a cylindrical ring, which may be cast in rubber, or made of rubber cloth, or other suitable material. It is fastened around the neck by means of a string passing through the loops B B, of which there are four, two only being shown. The ring or tube may be made round or with flattened surfaces, top and bottom.

C shows the valve by means of which I inflate the tube, or exhaust its contents, at pleasure.

A transverse section is shown in Figure No. 2, C.

A A, the tube.

D, a short piece of rubber pipe, fastened at one end into the tube; the other end clasps the valve-cage E.

G, a hollow rubber ball, one side of which clasps the outer end of the valve-cage, the other being supplied with a hole, I.

J shows the valve-seat.

K, the stopper, which should be made of rubber or leather.

L, the valve-stem, supplied with a knob or button at its outer end, and a spiral or other spring to keep the stopper in its seat.

N shows the spiral spring.

By placing the thumb on the opening or hole I, the fingers clasping the valve-cage, and pressing them together, the air contained in the ball G is forced through the valve and into the tube, the spring yielding to allow its passage, but closing the valve when the pressure is removed. By repeating, this process soon fills the tube with such air as is admitted to the ball G.

It may be inflated by blowing through the ball, when preferred.

The air may be removed from the inside of the tube, by pressing on the knob at the end of the valve-stem L.

When the air is to be used under water, for inhalation, the ball G is to be taken into the mouth, and pressure made on the knob.

What I claim as my invention, and desire to secure by Letters Patent, is—

The valve C and its ball G, in combination with a life-preserved, substantially as and for the purposes set forth.

E. S. BENNETT.
